Primary Examiner — Erich G Herbermann*Assistant Examiner* — Megan Tiana Rakos(74) *Attorney, Agent, or Firm* — Hayes Soloway P.C.(57) **CLAIM**

The ornamental design for a speaker as shown and described.

DESCRIPTION

1.1 is a front left-side perspective view of a speaker showing my new design;

1.2 is a front elevational view thereof;

1.3 is a back elevational view thereof;

1.4 is a top plan view thereof;

1.5 is a bottom plan view thereof;

1.6 is a left-side elevational view thereof; and,

1.7 is a right-side elevational view thereof.

The broken lines showing the "speaker" within the figures are for the purpose of illustrating the environmental structure and forms no part of the claimed design.

1 Claim, 7 Drawing Sheets(56)
